UNITED STATES PATENT OFFICE.

HANS LAUF AND MORITZ KLEBER, OF MAGDEBURG, GERMANY; SAID KLEBER
ASSIGNOR TO SAID LAUF.

TURRET-LATHE.

1,037,935.

Specification of Letters Patent. Patented Sept. 10, 1912.

Application filed June 8, 1910. Serial No. 565,876.

To all whom it may concern:

Be it known that we, HANS LAUF and MORITZ KLEBER, the first a subject of the King of Prussia, German Emperor, and the 5 second a subject of the King of Saxony, both residing at Magdeburg, Germany, have invented certain new and useful Improvements in Turret-Lathes, of which the following is a specification.

10 This invention relates to a turret-lathe with two simultaneously working turret-heads.

The essential feature of the invention consists in the arrangement according to 15 which each turret-head is mounted upon a separate bed in such a manner that the two turret-heads can be displaced upon their beds the one independently of the other. Owing to this improved arrangement both 20 turret-heads can work at the same time, the turret-lathe being thus adapted for the execution of any kind of work without requiring the shifting of the work-piece. The work to be executed can be of the most complicated kind, such as the turning of shafts, 25 spindles, hollow cylinders and facing in general. Herefrom follows that the time required for finishing a piece is reduced by one-half and that consequently the efficiency 30 of the lathe is doubled with regard to that of the turret-lathes of known construction.

The improved construction of the turret-lathe, that is to say, the use of separate beds for the two turrets and the arrangement according to which one of the turrets 35 is mounted vertically and the other horizontally and at right angles to the axis of the lathe, permits to simultaneously work short pieces by means of the tools of the 40 two turrets which have been brought the one very closely to the other. None of the turret-lathes of known construction offers this advantage, as it is impossible to approach the tools of the two turrets so that 45 they can simultaneously work a small piece. Further it is to be remarked that the turret-lathes of known construction present the inconvenience that very long tools have to be used which project a good 50 distance over the axle of the turret-head; this is necessary in order to avoid collision between the two turrets. These long tools are expensive, difficult to manipulate and they do not work very precisely. If, for 55 example, a hollow cylinder and its flange

has to be worked and if, for example, six tools are required for this operation, the tools of the two turrets must of course collide when the turrets slide upon one and the same bed; it is consequently impossible to operate both turrets simultaneously. 60

If a shaft has to be turned by one continuous cut from the end to the chuck it will be impossible to simultaneously approach the two turrets if they are mounted 65 upon one bed only, unless extremely long tools are used which project a good distance from the carriers. Such long tools permit only to cut a very thin chip and even then the work obtained is far from being 70 perfect.

According to the present invention both turrets can operate simultaneously which is impossible with the turret-lathes of known construction having their turrets 75 mounted upon one and the same bed. This is also the case if the two turret heads work closely at the face-plate, as with a turret-lathe improved according to the present invention the two heads can be brought quite closely 80 to the plane object, in order to simultaneously work the same. In the latter case the revoluble turret situated at an angle of 45° with regard to the axis of the lathe and adapted to be adjusted horizontally is 85 particularly advantageous. The turret-head which is revolubly mounted so that it can be adjusted and which stands at right angles with regard to the axis of the lathe could further be mounted upon a cross slide. 90 With a lathe of this particular construction the most complicated operations on hollow cylinders can be executed and inner threads could be cut very easily.

The present invention can be applied to 95 turning-lathes of any type. The driving gears can be operated by hand, semi-automatical or automatical.

In the accompanying drawings several modifications of an improved turret-lathe 100 are shown.

Figure 1 represents in ground plan a turret-lathe having one turret-head which is adjustable and mounted horizontally at right angles to the axis of the lathe and a second 105 turret-head revolubly mounted on a vertical shaft. Fig. 2 is an elevation and Fig. 3 a right hand end view of the turret-lathe Fig. 1. Fig. 4 represents a turret head mounted in trunnions and rotatable about an axis at 110

right angles to the trunnions; Fig. 5 is an elevation and Fig. 6 is a right hand side end view of the lathe shown in Fig. 2. Figs. 7 and 8 show in elevation and in plan view 5 certain parts of the lathe according to Figs. 1 to 3 for turning a long spindle.

From Figs. 1 to 3 the simultaneous drilling of a work 1 can be seen. The turret-head 3 mounted upon the bed 2 serves for 10 drilling the work 1, and the turret-head 6 mounted upon the slide 5 and the bed 4 serves for turning or surfacing the cylinder by means of the tool 7. It is easy to understand, that at the next feed the turret-head 15 6 operates with its tool 8 upon the plane surface 9 of the work 1 without being impeded in the least by the revoluble tool 10 of the turret-head 3.

Figs. 4 to 6 illustrate how a hollow work 20 is operated upon. The turning tool 11 of the turret-head 12 operates simultaneously with the turning tool 13 upon the inner part of said work 14. It would be impossible to execute this operation with the turret-head 25 6 (Figs. 1 to 3) as there are several other tools 11 required for turning the hub of the work 14 to its bottom surface. The turret head 12 therefore is arranged obliquely to the spindle of the lathe, the angle of obliquity being preferably 45°. Thus it is possible 30 that the four equal tools 11 (Figs. 4 to 6) are neither hindered by the work 14 nor by the turret-head 3 when they are being moved toward the place where they have to 35 work.

Figs. 7 and 8 show how a long spindle is worked and made from iron rods. The turret-head 3 carries the chuck 15 for the knife, the guide-sleeve 16 and the center 27. The 40 turret-head 6 carries the tools 17, 8, 18 and 19.

The operation is as follows:—The turret-head 3 serves for turning the spindle 20 by means of the knife-head 15 which has a collar-plate. During this turning operation the 45 turret-head 6 cuts by means of the tool 17, the journal 21 and then the bearing surface 22. At the end of this operation the knife head 15 and the turret-head 3 have arrived 50 at the chuck 23. The turret-head 3 is here-

upon withdrawn and the center 27 used for centering the journal 21. The turret-head 6 has passed along the turret-head 3 and turns now the other bearing surfaces 24, 25. The cutting off of the spindle is effected by 55 the tool 18. If the spindles should be thin and therefore the centering by means of the center 27 be impossible owing to the vibrations, the turret-head 3 is to be used as a collar-plate for the further operations. 60

According to the present invention the turret-head 3 can serve in lieu of the sliding-puppet of an ordinary lathe. This characteristic feature of the invention proves the advantage of the separate beds as otherwise 65 the turret-head could not work along the entire length of the bed without being impeded by the ordinary head.

We claim.—

1. An improved turret-lathe with two 70 simultaneously operating heads comprising in combination with the main spindle, a bed guide, a turret head in said bed guide revoluble around a horizontal axis which stands perpendicular to the longitudinal 75 axis of the main spindle, a second bed guide parallel with the first bed guide and a head mounted in said second bed guide so that it can revolve around a vertical axis.

2. An improved turret-lathe with two 80 simultaneously operating heads comprising in combination with the main spindle, a bed guide, a turret head in said bed guide revoluble around a horizontal axis which stands perpendicular to the longitudinal 85 axis of the main spindle, a second bed guide parallel with the first bed guide and a head mounted in said second bed guide so that it can revolve around a vertical axis, said second revolving head being adjusted with regard to the longitudinal axis of the main 90 spindle, substantially as described and shown and for the purpose set forth.

In witness whereof we have hereunto set our hands in the presence of two witnesses. 95
